Elihu Walker.

Letters Patent

With the schedule referred to in these Letters Patent and making part of the same, containing a description in the words of the said Elihu Walker himself of his improvement in making saddles.

But while of one entire piece of leather the skirt or jockey of the seat, the front or back part of the saddle, and the back part of the draw-down, so as to have the saddle made and not have it scanned up in the usual form, or in any other manner the workman shall choose, as far back as is necessary. Back of the skirt or jockey the seat is to draw under the saddle tree, for a draw down, to make the seat and the skirt or jockey on with the draw down, is a piece of leather sewed on the under side of the skirt or jockey to draw under the saddle to nail the skirt or jockey and the seat on with.

Witness,

Elihu Walker.
